UNITED STATES PATENT OFFICE

HARRY E. KNUPP, OF DETROIT, MICHIGAN, ASSIGNOR TO CAILLE MOTOR COMPANY,
OF DETROIT, MICHIGAN, A CORPORATION OF MICHIGAN

DESIGN FOR A SCALE

Application filed October 21, 1930. Serial No. 37,333. Term of patent 7 years.

To all whom it may concern:

Be it known that I, HARRY E. KNUPP, a citizen of the United States, and a resident of Detroit, in the county of Wayne and State of Michigan, have invented a new, original, and ornamental Design for Scales, of which the following is a specification, reference being had to the accompanying drawing, forming part thereof.

Figs. 1 and 2, respectively, are front and side elevation views of the scale showing my new design.

What I claim is:

The ornamental design for a scale substantially as shown.

Signed at Detroit, Mich., Oct. 15, 1930.

HARRY E. KNUPP.
